UNITED STATES PATENT OFFICE.

HARRY F. HANSEN, OF WASHINGTON, DISTRICT OF COLUMBIA.

HEADLIGHT ATTACHMENT.

Application filed November 6, 1923. Serial No. 673,106.

To all whom it may concern:

Be it known that I, HARRY F. HANSEN, a citizen of the United States, residing at Washington, in the District of Columbia, 5 have invented new and useful Improvements in Headlight Attachments, of which the following is a specification.

The present invention relates to attachments for headlights; and its main object, 10 stated briefly, is the provision of an improved device which may be readily fitted in a headlight of either the conoidal or the drum type now in general use, to block or mask the upwardly-reflected rays emitted 15 by the source of light, leaving only those rays which are projected forward in a horizontal or downward direction, whereby a non-glare headlight is thus obtained without resort to the use of a specially constructed 20 reflector or other adjuncts.

A further object of the invention is to provide an attachment of the character indicated which, in itself, is not only extremely simple and inexpensive to manufacture, but 25 which may be made and sold in stock sizes, so that it can be installed in any of the standard types of headlights now on the market, whether as a part of the factory equipment of a car, or as an accessory for 30 new or second-hand cars.

The invention also contemplates the formation of the attachment in two separate members which are of a counterpart construction, excepting as to the arrangement 35 of the reflecting and non-reflecting surfaces thereof, so that in the event of injury to either member, that member may be removed from the casing and replaced by another one without requiring a complete new attachment to be purchased; the counterpart 40 feature referred to enabling both members to be constructed with a single set of dies.

According to the invention, the improved non-glare attachment consists of upper and 45 lower members of counterpart size and shape which are fitted in the casing of the headlight directly in front of the reflector and in spaced relation to each other, leaving between them a central gap or chamber into 50 which the electric light bulb or other source

of light projects. Each of these members has the form of a dihedral angle, the two wings of which are perpendicular to each other, one wing being arranged vertically, and at the front of the casing, while the other wing is disposed horizontally and projects rearwardly from the inner edge of the first wing. The vertical wings of both members have their front surfaces blackened so as to mask the corresponding portions of 60 the headlight and thus limit its bright portion to the light-containing chamber just mentioned, and the upper or outer surface of the horizontal wing of the lower member is also blackened to absorb the light rays 65 which strike against it; but the outer surface of the horizontal wing of the upper member, on the contrary, is highly polished so that it will thus constitute a reflector for coaction with the exposed portion of the wall 70 of the reflector proper.

Due to this construction and arrangement of parts, it will be obvious that a segment-shaped portion of the headlight, both at the 75 top and at the bottom thereof, will be masked; and that between these two masked portions there will be left an intermediate portion or chamber having the appearance of a horizontally-disposed, elongated rectangle of comparatively small height. The vertical wall of this chamber is constituted by the exposed portion of the reflector wall and has, in consequence, a reflecting action 80 on the light rays, and its horizontal top wall likewise exerts an action of the same nature; 85 but the horizontal bottom wall, on the contrary, is incapable of exerting any reflecting action, owing to its having been blackened, the result being that the light beam projected from the headlight will travel in a 90 substantially horizontal direction only, all rays which would otherwise be reflected being intercepted and absorbed by the blackened horizontal wall or surface specified. 95 All danger of blinding or dazzling the eyes of drivers of vehicles approaching from the opposite direction is thereby avoided, because the plane of the beam will be disposed too low for that to occur.

An embodiment of the invention is illus- 100

trated in the accompanying drawings, in which:

Figure 1 is a front view of a conventional drum headlight equipped with the attachments;

Fig. 2 is a central vertical section;

Fig. 3 is a perspective view of the upper attachment;

Fig. 4 is a rear view thereof;

Fig. 5 is a perspective view of the lower attachment.

Referring more particularly to the drawings, 1 indicates the casing of the lamp; 2, its hinged front member or door, which carries the glass plate, panel or lens 3; 4, the reflector and 5 the electric light bulb or other source of light. The casing 1 is here shown as of the drum type now in general use, though it may be of conoidal shape, if preferred, or of any other suitable form; and the reflector 4 is likewise of conventional parabolic type, with the bulb or lamp 5 mounted at the center thereof as usual, said reflector being provided at its marginal edge 25 with a lateral flange 4'. The glass panel 3 may also be of any preferred type. As will be understood from the foregoing, the essential feature of my invention is the provision of an accessory or attachment for a drum or other conventional type of headlight which is constructed as a separate and distinct entity from the headlight and may be installed therein and removed therefrom at will, as circumstances require. This attachment consists of two counterpart light obstructing members 6 and 7, constructed of sheet metal and comprising, each, a vertical wing 6' or 7' and a rearwardly-extending, horizontal wing 6² or 7², as illustrated in Figs. 3 and 5. The two wings of each member are disposed perpendicularly to each other so as to form a right dihedral angle; the horizontal wings being located at the bottom of the upper member and at the top of the lower member and being of parabolic shape so as to enable them to fit conformably within a standard reflector. The vertical wings are made approximately segmental or semi-circular for the same reason, and their curved marginal edges are provided with felt strips 8 which are secured to the front faces thereof to contact with the glass plate 3 for the purpose of preventing rattling.

Where the sheet metal used is sufficiently stiff and heavy to enable the light obstructing members to maintain their dihedral form, they may be mounted directly in the casing without the addition of any further parts, and secured in place by screws or other removable fastenings which are inserted through registering holes in the aforesaid flange and edges. But where thinner metal is used, it is advisable to provide each member with one or more metal bracing straps 9

(Fig. 4) which are fastened at opposite ends to the wings and thus prevent their deformation.

As previously stated, the two members 6 and 7 are fitted in the upper and lower portions of the reflector, with their horizontal wings 6² and 7² opposite each other and in spaced, parallel relation, thereby leaving between them an intermediate horizontal chamber which extends diametrically of the reflector, so as to permit the lamp 5 to project thereinto; the back and sides of the chamber being formed by the exposed portion of the reflector wall which, as will be understood, is polished or otherwise treated to produce a reflecting action. The purpose of this chamber is to localize or condense the light rays and to intercept and absorb all those which would ordinarily be reflected upward. Accordingly, the upper or outer surface of the horizontal wing 7² of the lower member 7 is blackened or treated in some similar way to render it light-absorbent, whereas the lower or outer surface of the horizontal wing 6² of the upper member 6 is silvered or polished. The vertical wings 6' and 7' are disposed in the front of the reflector, parallel with and in close proximity to the glass panel 3, and their outer faces are likewise blackened.

By reason of the counterpart construction of the two members, it will be apparent that they can be stamped or cut from the sheet metal blanks by means of a single set of dies, instead of necessitating two sets as would be the case if the members were of different shapes; the steps of silvering or polishing and painting being carried out subsequently. Hence the members can be manufactured and sold in bulk to fit the standard sizes and types of headlights commonly used, so that the production cost is thereby reduced practically to a minimum. Furthermore either member may be detached at any time, when necessary for one reason or another, merely by removing the fastening screws, and, if damaged, can be readily replaced by a new member at little expense.

I claim as my invention:

1. An attachment for vehicle headlights, comprising a pair of structurally-separate light-obstructing members, each in the form of a dihedral angle embodying a vertical wing and a horizontal wing and adapted to be removably positioned in the upper and lower portions of the reflector of a headlight in inverted relation, with their horizontal wings parallel and spaced apart to provide between them a diametral chamber into which the secure of light projects and the back and sides of which are formed by the wall of the reflector, the horizontal wings of the upper and lower members having light-reflecting and light-absorbing outer surfaces, respectively, substantially as described.

2. An attachment according to claim 1, in which the two light-obstructing members are of counterpart size and shape, the vertical wing of each member being approximately segmental and the horizontal wing parabolic so as to fit conformably in the reflector, substantially as described.

3. An article of manufacture for use in vehicle headlights to avoid blinding, com-

prising a flat, plate-like wing of approximately segmental shape and a second flat, plate-like wing having the shape of a parabola, said wings being connected together to conjointly form a dihedral angle, and bracing means connecting the backs of said wings, substantially as described. 10 15
